ATOMIZER

Warren C. Graham, New York, N. Y.

Application March 15, 1937, Serial No. 130,877

5 Claims. (Cl. 299—120)

This invention relates to mechanical atomizers or sprays for liquids, for example, atomizers for burners using liquid or colloidal fuels. More specifically, the invention relates to atomizers of the whirling spray type, in which the liquid issues from a tip, sprayer plate or nozzle with a spinning motion which causes the spray to assume the shape of a cone, preferably a hollow cone.

10 The object of the invention is to improve the atomizing qualities of such devices, so that a finer spray may be produced than has heretofore been attainable or a lesser feed-pressure may be employed to produce sprays of the degree of fineness realized by the best known atomizers.

In the accompanying drawing and description, the invention has been illustrated as applied to a preferred and well-known type of liquid fuel atomizer in which the fuel is delivered to a series of slots or conduits disposed transversely and tangentially to the axis of the atomizer and communicating with a central whirl chamber from which the atomizer orifice leads. While the invention in its broadest aspect, may take other forms, it is particularly adapted to the type of atomizer mentioned.

Broadly, the invention comprises means which imparts a whirling motion to a flowing stream of liquid, delivers the whirling stream into an expansion chamber, wherein the heavier particles are separated from the lighter by centrifugal force, and conducts the separated particles to the orifice of a spray nozzle. More specifically the invention comprises a device in which the whirling stream of liquid is delivered to the tangential slots of an atomizer of the preferred type above-mentioned.

In the drawing:

Figure 1 is a longitudinal section of a spray nozzle constructed in accordance with the invention.

Figures 2 and 3 are cross-sections on the line designated 2—2 or 3—3 in Figure 1, the said views looking in opposite directions, and

Figure 4 is a developed or diagrammatic view on a larger scale, showing the relations of some of the liquid passages.

In the drawing, 1 designates a supply pipe for liquid fuel or other liquid. This pipe is provided with an externally threaded nipple 2 upon which is screwed body member 3 of a spray nozzle. The body member has a reduced externally threaded extension 4 upon which is screwed a gland nut 5. The gland nut has an inner flange 6 which clamps a spray tip 7 against the end of body

member 3. It will be noted that, except for certain recesses and passages, hereinafter referred to, the outer end of body member 3 is closed by a plug or partition 8. The central part of spray tip 7 bears against plug 8 and its periphery is seated upon a shoulder 9 formed on the body member.

Spray tip 7 is of usual construction. It has an orifice 10 communicating with a whirl chamber 11 and tangential slots 12 which lead into the whirl chamber at its periphery. The outer and inner faces of the spray tip are preferably flat, as shown. The ratio of the total area of the tangential slots to the size of the orifice is of great importance and this ratio may be varied to produce corresponding changes in the size, shape and other characteristics of the resulting spray or flame.

Immediately behind the inner face of the spray tip, I provide an auxiliary whirl chamber 13, which, in conjunction with means for supplying whirling liquid to the chamber, comprises the most essential feature of the invention. Chamber 13 is preferably of the annular form shown, being bounded outwardly by the wall of extension 4 and inwardly by plug 8. Any suitable means may be utilized for imparting a whirling motion to the liquid before it enters the chamber 13. The means shown is one of several well-known devices for this purpose. It comprises a series of inclined holes 14 running through plug 8. The inclination is in the angular or circular direction, either clockwise, as shown, or anti-clockwise.

The effect of whirling the liquid before it enters the tangential slots is as follows: If the liquid is composed of a mixture of particles of varying densities, such as fuel oil, centrifugal force will throw the heavier particles outwardly in whirl chamber 13 and thus separate them from the lighter particles. Before the particles adhere again to form a homogeneous mixture, they are forced into the tangential slots, thence into whirl chamber 11 where they are broken down into still finer particles, and finally through the orifice of the sprayer tip. Subdivision of the particles is further aided by the rapid movement of the stream of liquid in whirl chamber 13 in a circular direction, i. e., across the tangential slots. While some of the particles enter the nearest slot and others sweep past to enter succeeding slots, still other particles impinge upon the trailing shoulders or corners of the slots and are broken up by the shearing effect thus produced.

5 The spinning of the fuel in whirl chamber 13 and subsequent delivery to the tangential slots, should not be confused with the barreling effect employed in some existing oil burners for the mere purpose of rotating the fuel before it leaves the sprayer tip. Such a device will not produce as high a degree of atomization as my improvement.

10 In existing oil burners, i. e., those employing sprayer tips of the tangential slot type, it has been found that the maximum obtainable atomization is produced by a pressure of 300 lbs. With pressures below 300 lbs., atomization is inadequate and higher pressures do not noticeably increase 15 the fineness of the spray. Tests have shown that the addition of my improvements to an otherwise standard sprayer tip makes it possible to produce the maximum atomization heretofore obtainable with a pressure of 150 lbs. Moreover, 20 when higher pressures up to 300 lbs. are used, the spray is finer than any heretofore known.

25 It will be observed that the diameter of the central solid portion of plug 8 determines how much of the tangential slots shall be open to whirl chamber 13, the remainder of the slots constituting ducts into whirl chamber 11. By making this diameter larger or smaller, the length of travel in the slots is varied and corresponding changes in the characteristics of the 30 spray result.

I claim:—

1. A spray nozzle comprising in combination, a sprayer tip having an orifice and tangential slots communicating therewith, a whirl chamber 35 behind the sprayer tip and communicating with the slots, and means for delivering whirling liquid to said whirl chamber.

2. A spray nozzle comprising in combination, a sprayer tip having an orifice and a whirl cham-

ber and tangential slots communicating with the whirl chamber, an annular auxiliary whirl chamber behind the sprayer tip and communicating with the slots, and means for delivering whirling liquid to the auxiliary chamber. 5

3. A spray nozzle comprising in combination, a sprayer tip having an orifice and a whirl chamber and tangential slots communicating with the whirl chamber, an annular auxiliary whirl chamber behind the sprayer tip and communicating 10 with the slots through a portion of their lengths at their outer ends, and means for delivering whirling liquid to the auxiliary chamber.

4. A spray nozzle comprising in combination, a sprayer tip having an orifice and a whirl chamber and tangential slots communicating with the whirl chamber, the slots being open rearwardly for only a portion of their lengths at 15 their outer ends, an annular auxiliary whirl chamber behind the sprayer tip and communicating with the open portions of the slots, and means for delivering whirling liquid to the auxiliary chamber. 20

5. A spray nozzle comprising in combination, a sprayer tip having an orifice and a whirl chamber 25 and tangential slots communicating with the whirl chamber, the whirl chamber and slots being open rearwardly, a hollow body member behind the sprayer tip, the body member having, first, an opening for the admission of liquid under 30 pressure, and second, a front wall lying across the rear face of the sprayer tip, the front wall having an annular recess in its front face adjacent the outer ends of the tangential slots, and holes connecting the interior of the body member with the annular recess, the holes being inclined in a direction having a tangential component with respect to the annular recess. 35
